Fig. 1.1 shows a perspective view of the chair; Fig. 1.2 shows a front view of the chair; Fig. 1.3 shows a right side view of the chair; Fig. 1.4 shows a left side view of the chair; Fig. 1.5 shows a bottom view of the chair; Fig. 1.6 shows a back view of the chair; Fig. 1.7 shows a top view of the chair. The broken lines shown in the drawings are for the purpose of illustrating portions of the article that form no part of the claimed design. The design shows a chair, which consist of a seat and a frame; figures 1.6 and 1.6 depict eight vertical lines at the outermost part of the seat—opposite the backrest of the seat; these eight vertical lines illustrate how the outermost part of the seat is fixed at the frame of the chair for the seat to seal tightly and to avoid budging during use; figures 1.3 and 1.4 depict a curved line that illustrates the right and left side view of the eight vertical lines as seen on figures 1.5 and 1.6; the curved lines on figures 1.3 and 1.4 are placed between the seat and the frame to illustrate that the curved lines are fitted tightly around the frame for the seat to seal tightly.
